UNITED STATES PATENT OFFICE

WILLIAM O. ISAACSON, OF CHICAGO, ILLINOIS

BUCK SUPPORT

Application filed May 29, 1930. Serial No. 457,193.

This invention relates to supports, and with regard to certain more specific features, to supports for door bucks, window frames and like building units.

Among the several objects of the invention may be noted the provision of universally adjustable, portable means for supporting a door buck or the like in position, prior to building around it and permanently supporting it by extraneous building construction; the provision of a device of the class described which is readily adaptable to supporting the buck in various locations; and the provision of a device of the class described which is light, easy to carry about and simple to apply. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claims.

In the accompanying drawings, in which are illustrated several of various possible embodiments of the invention,

Fig. 1 is a perspective view showing the application of the support to a door buck;

Fig. 2 is a plan view of the support in folded position, ready for transportation;

Fig. 3 is a detailed section of a slide and a guide therefor taken approximately on line 3-3 of Fig. 1; and,

Fig. 4 is a side elevation of a gripping screw.

Similar reference characters indicate corresponding parts throughout the several views of the drawings.

Referring now more particularly to Fig. 1, there is illustrated at numeral 1, the corner of a door buck which is exemplary of many members to which the present invention is applicable. This corner is representative of a pair of such corners on every door buck.

It will be appreciated that bucks of this type and similar objects in building constructions are set with their lower ends on the floor or the like; and there then arises a problem as to how to support and accurately align the upper end, prior to applying the ordinary supports which are provided for the bucks as the construction proceeds. The difficulties which have been met are that there are bucks of various sizes which are adapted to be put into various locations. Thus it requires different lengths of supports and/or struts in order to reach to walls, ceilings or the like, for supporting purposes. Another difficulty has been that the bucks have been mutilated in applying makeshift devices thereto, such as nailed braces. My invention solves these and other difficulties and provides added improvements not found heretofore.

Referring again in particular to Fig. 1, it will be seen that the support per se comprises a right and left-hand pair of braces 3, spaced from one another and adapted to be applied to opposite sides of a buck or the like. Each brace 3 comprises a corner plate 5 to which is riveted or otherwise rigidly fastened a strut 7. Adjacent each strut 7 is pivoted to the corner plate 5, a double slotted guide 9, along which is movable a slide 11.

The relationship between each slide 11 and its guide 9 is shown more particularly in Fig. 3, this figure also showing the application of a locking screw and nut combination 13 through one guide slot for clamping and unclamping the slide 11 to and from the guide 9. It will thus be seen that each slide 11 may be positioned and locked in any given location or elevation on its guide 9.

Hinged to each slide 11 is a side arm brace 15 swingable in a plane at substantially a right angle to the swing or plate 5 of its respective guide 9. The purpose of the side arm braces 15 is to provide lateral support for the buck 1, said support being such that a reaction may be applied against ceiling or

like surfaces of varying elevation, by suitable adjustment of the slides 11 in their guides 9 and by suitable swinging adjustments of the lateral braces 15 on their slides 5 11.

In order that given positions of the lateral braces 15 may be maintained in respect to the slides 11, there is provided on each slide 11 a pin 17 extending through the pair of slots 10 in the guide 9 and between the legs which comprise the respective lateral supports 15. An adjusting nut 19, threaded to each pin 17, controls the swing of the respective lateral braces 15. The action of the wing nuts 19 15 is for adjustment, and inasmuch as they are on one side only of the laterally swingable members, they do not prevent folding up of the laterally swingable members 15 against the guides 9. The folding up may be done 20 quickly without requiring that the wing nut 19 be adjusted.

It will be seen that the adjusting feature of the wing nuts 19 in connection with the side arm braces 15 may be used for obtaining 25 a reaction to adjust the position of the buck 1 exactly. For instance, the support as a whole may be clamped to the buck and the slides 11 run up into position such that a reaction is obtained between pieces 21 and the 30 ceiling, as shown in the drawings. Thereafter, the wing nut 19 may be drawn up so that the buck is forced one way or another, as desired, to obtain an accurate alignment of the buck. At the upper ends of the lateral 35 braces 15 the pivoted channel shaped pieces 21 function both as supporting feet (see the left side of Fig. 1) or as extensions (see the right side of Fig. 1). When functioning as extensions, the members 21 are limited in 40 their angular rotation on the respective braces 15 by the fact that the ends of the braces 15 lie in the channel space and the tendency to turn, caused by a reaction against the ceiling, is thus limited. It will be seen 45 from Figs. 1 and 2 that the side braces 3 may be folded up by laying them against the guides 9 and running their sliders 11 down to the bottoms of the guides 9 and then folding the guides 9 against the struts 7. The 50 supporting members 21 may also be rotated into position substantially parallel with the length of the then parallel members 7, 9, and 15.

In order that the side braces 3 may be held 55 together as a unit and at the same time be applicable to various bucks, window jambs, and the like they are connected by a plurality (three in the present instance) of draw screws 23. One of these draw screws connects the plates 5, one connects the ends of the struts 7, and another connects the ends of the guides 9. Each screw passes through an opening at one end of a U-shaped member 25 connected to one of the braces 3. Within 65 each U-shaped member is a non-rotatable nut

into which passes said screw. Each screw 23 at its other end passes through a collar 26 which permits rotation of the screw without longitudinal movement. Thus it is possible by means of cranks 27 connected to the screw, 70 to draw the side braces 3 together or to permit them to be separated. Hence there is effected a clamping action on the bucks by the screw-connected braces 3.

In order that the buck may be positively 75 gripped by the clamps or braces 3, the ends of the struts 7 and the guides 9 are provided with threaded members 29 the inner ends of which are pointed as shown at numeral 28 in Fig. 4 and the outer ends of which have handles 31. By this means a definite grip may be effected on the wood of the bucks, which grip may be adjusted to a degree which will not substantially mar the surface of the 80 bucks as would nails.

It will be understood that although the above description shows only one corner of a buck, that a device such as herein disclosed may be applied to each corner.

Re the feet 21, it will be seen that when used flat, (left of Fig. 1) they may be used against finished surfaces, such as lathed or plastered ones, whereas when used as shown at the right of Fig. 1, it is preferable that harder surfaces such as concrete or the like be available.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as 100 illustrative and not in a limiting sense.

I claim:

1. A support of the class described comprising clamping members adapted to be drawn together on a building device, each member comprising a strut and a guide, sliding means on said guides, and laterally swingable braces on said sliding means.

2. A support of the class described comprising clamping members adapted to be drawn together on a building construction, each member comprising a strut and a guide, sliding means on said guides, and laterally swingable braces on the sliding means, said guides and said strut being relatively swingable whereby the apparatus may have all of the guide and bracing members laid substantially parallel.

3. A support of the class described comprising clamping members adapted to be drawn together on a building construction, each member comprising a strut and a guide, sliding means on said guides, and laterally swingable braces on said sliding means, said 125

sliding means on the two guides being movable independently of one another.

4. A support of the class described comprising clamping members adapted to be drawn together on a building device, each member comprising a strut and a guide, sliding means on said guide, laterally swingable braces on said sliding means and extensible members at the ends of said laterally movable braces.

5. A device of the class described for supporting and adjusting parts of a building construction comprising a clamping means adapted to be attached to one of said parts of a building construction, guide ways included with said clamping means, slidable elements on the guide ways and relatively movable members on said sliding elements adapted to effect reaction against extraneous surfaces.

20 6. A device of the class described for supporting and adjusting parts of a building construction comprising a clamping means adapted to be attached to one of said parts of a building construction, guide ways included with said clamping means, slidable elements on the guide ways, laterally swingable members on said sliding elements adapted to effect a reaction against extraneous surfaces and extensible means on said laterally swingable member.

7. A device of the class described for supporting and adjusting parts of a building construction comprising a clamping means adapted to be attached to one of said parts of a building construction, guide ways included with said clamping means, slidable elements on the guide ways, laterally swingable members on said sliding elements adapted to effect a reaction against extraneous surfaces and mechanical adjusting means between the laterally swingable members and the slidable elements permitting forcing the building construction to alignment by the reaction obtained.

45 8. A device of the class described for supporting and adjusting parts of a building construction comprising a clamping means adapted to be attached to one of said parts of a building construction, guide ways included with said clamping means, slidable elements on the guide ways, laterally swingable members on said sliding elements adapted to effect a reaction against extraneous surfaces, mechanical adjusting means between the laterally swingable members and the slidable elements permitting forcing the building construction to alignment by the reaction obtained and means for folding the laterally swingable members into parallel position with respect to their guides, the folding operation being independent of said adjusting operation.

9. In a device of the class described, a clamping member adapted to be attached to the sides of a construction unit, vertically ad-

justable means associated with said clamping means and lateral swingable braces pivoted to said vertically adjustable means.

10. In a device of the class described, a clamping member adapted to be attached to the sides of a construction unit, vertically adjustable means associated with said clamping means, lateral swingable braces pivoted to said vertically adjustable means and mechanical means for swinging said laterally swingable braces upwardly to react against an extraneous surface.

11. In a device of the class described, a clamping member adapted to be attached to the sides of a construction unit, vertically adjustable means associated with said clamping means, lateral swingable braces pivoted to said vertically adjustable means, mechanical means for swinging said laterally swingable braces upwardly to react against an extraneous surface and extensions on said laterally swingable means.

12. In a device of the class described, a pair of clamping elements, screw means for drawing said clamping elements together against opposite sides of a building unit, adjustable gripping means associated therewith, said clamping elements comprising corner struts and pivoted guide members, slide members movable along said guide members, laterally swingable arms pivoted to said slide members and mechanical means for causing a reaction of said arms against an extraneous surface.

13. In a device of the class described, a pair of clamping elements, screw means for drawing said clamping elements together against opposite sides of a building unit, adjustable gripping means associated therewith, said clamping elements comprising corner struts and pivoted guide members, slide members movable along said guide members, laterally swingable arms pivoted to said slide members and mechanical means for causing a reaction of said arms against an extraneous surface, said slide members being movable independently of each other.

14. In a device of the class described, a pair of clamping elements, screw means for drawing said clamping elements together against opposite sides of a building unit, adjustable gripping means associated therewith, said clamping elements comprising corner struts and pivoted guide members, slide members movable along said guide members, laterally swingable arms pivoted to said slide members, mechanical means for causing a reaction of said arms against an extraneous surface, said slide members being movable independently and extensible means at the ends of said laterally swingable members.

15. A support of the class described comprising clamping members adapted to be drawn together on a building construction, each member comprising a strut and a guide, sliding means on said guides, laterally swing-

able braces on the sliding means, said guides and said strut being relatively swingable whereby the apparatus may have all of the 5 guide and bracing members laid substantially parallel and pivoted feet on said laterally swingable braces adapted also to be folded parallel to said other members.

In testimony whereof, I have signed my name to this specification this 27th day of 10 May, 1930.
